DESIGN FOR A NAMEPLATE

William J. Adams, Jr., Hartsdale, N. Y., assignor to Bell Telephone Laboratories, Incorporated,
New York, N. Y., a corporation of New York

Application December 28, 1934, Serial No. 54,631

Term of patent 14 years

To all whom it may concern:

Be it known that I, William J. Adams, Jr., a citizen of the United States of America, residing at Hartsdale, in the county of Westchester and State of New York, have invented a new, original, and ornamental Design for a Nameplate, of which the following is a specification, reference being had to the accompanying drawing, forming a part thereof.

Fig. 1 of the drawing is a front face plan view of the nameplate and shows my new design; and

Fig. 2 is a view in cross-section of the nameplate taken on the line 2—2 in Fig. 1 and viewed in the direction indicated by the arrows.

Figs. 1 and 2 are drawn to the same scale.

I claim:

The ornamental design for a nameplate as shown.

In witness whereof, I hereunto subscribe my name this 26th day of December, 1934.

WILLIAM J. ADAMS, JR.
